UNITED STATES PATENT OFFICE

170,874

FOOD WASTE DISPOSER OR THE LIKE

Raoul A. Lambert, Springfield, Mass., assignor to
Westinghouse Electric Corporation, a corpora-
tion of Pennsylvania

Application July 8, 1952, Serial No. 20,512

Term of patent 14 years

(Cl. D55—1)

To all whom it may concern:

Be it known that I, Raoul A. Lambert, a citizen of the United States, residing at Springfield, in the county of Hampden and State of Massachusetts, have invented a new, original and ornamental Design for a food waste disposer or the like, of which the following is a specification, reference being had to the accompanying drawing, forming a part thereof.

Figure 1 is a front perspective view of a food waste disposer incorporating my new design; and

Figure 2 is a slightly reduced side elevational view thereof.

The dominant features of the design reside in the portions shown in full lines.

I claim:

The ornamental design for a food waste dis-
poser or the like, substantially as shown and
described.

RAOUL A. LAMBERT.
